UNITED STATES PATENT OFFICE

159,918

COVERED COOKING UTENSIL

Peter Muller-Munk, Pittsburgh, Pa., assignor to Ekeo Products Company, Chicago, Ill., a corporation of Illinois

Application April 20, 1948, Serial No. 145,854

Term of patent 7 years

(Cl. D44—1)

To all whom it may concern:

Be it known that I, Peter Muller-Munk, a citizen of the United States, residing at Pittsburgh, county of Allegheny, State of Pennsylvania, have invented a new, original, and ornamental Design for a Covered Cooking Utensil, of which the following is a specification, reference being had to the accompanying drawing, forming part thereof.

Fig. 1 is a side elevational view of a covered cooking utensil, showing my new design.

Fig. 2 is a top plan view.

Fig. 3 is an end elevational view when viewed from the right of Fig. 1.

I claim:

The ornamental design for a covered cooking utensil, as shown.

PETER MULLER-MUNK.
